[57] CLAIM

The ornamental design for a dispensing closure, as shown and described.

DESCRIPTION

FIG. 1 is a plan view of a dispensing closure showing my new design;

FIG. 2 is a front elevational view;

FIG. 3 is a side elevational view;

FIG. 4 is a rear elevational view;

FIG. 5 is a bottom plan view; and

FIG. 6 is a top plan view with the hinged element in a fully opened position.

The broken lines showing of the dispensing port is for illustrative purposes only and forms no part of the claimed design.
